UNITED STATES PATENT OFFICE.

DEXTER BOOK STEPHENS, OF YOUNGSTOWN, OHIO.

DESIGN FOR A KEY-FASTENER.

SPECIFICATION forming part of Design No. 27,362, dated July 13, 1897.

Application filed February 13, 1897. Serial No. 623,322. Term of patent 7 years.

To all whom it may concern:

Be it known that I, DEXTER BOOK STEPHENS, a citizen of the United States, residing at Youngstown, in the county of Mahoning and State of Ohio, have invented a certain new and useful Design for Key-Fasteners, of which the following is a specification, reference being had therein to the accompanying drawings.

- 10 My invention relates to key-fasteners or devices adapted to secure keys in the key-sockets of locks, whereby any tampering or picking of the said lock from the outside thereof may be effectually frustrated.
- 15 In disclosing fully the design and configuration of my said invention I will make use of the accompanying drawings, in which—
Figure 1 is a view of my key-fastener, and
Fig. 2 is a side view thereof.

The same numeral always indicates the same part.

1 is the key-fastener, stamped or otherwise made from a flat plate into the approximate triangular form, and at one end thereof is the circular opening 2. At the other end of 25 the said fastener is a projecting lug 3, forming a shoulder 4 of a rectangular form.

Having fully described my invention, I desire to secure and claim—

The design for a key-fastener as herein shown and described.

In testimony whereof I affix my signature in presence of two witnesses.

DEXTER BOOK STEPHENS.

Witnesses:

J. M. WEIRICK,
JOSEPH DAVIS.
